(57) **CLAIM**

The ornamental design for a gasket for a food processing system, as shown and described.

DESCRIPTION

FIG. 1 is a perspective view of a gasket for a food processing system showing our new design, with the food processing system being shown in phantom lines for environmental purposes only and not being part of the claimed invention; FIG. 2 is a top, front, right side perspective view of a gasket for a food processing system showing our new design; FIG. 3 is a bottom, front, left side perspective view thereof; FIG. 4 is a top plan view thereof; FIG. 5 is a bottom plan view thereof; FIG. 6 is a left side elevational view thereof; FIG. 7 is a right side elevational view thereof; FIG. 8 is a front elevational view thereof; FIG. 9 is a rear elevational view thereof; and, FIG. 10. is a sectional view thereof taken substantially along line 10—10 of FIG. 4.
